ACCELERATOR SETTING CONTROL

James T. Reilly, Laguna Beach, Calif.

Application April 9, 1951, Serial No. 219,978

17 Claims. (Cl. 192—3)

1

This invention relates to automobile accelerator controls and particularly to improved foot controlled means for releasably maintaining an accelerator in a set position when it is desired to travel at a constant speed for a relatively extended period.

Though various foot controlled accelerator setting devices have heretofore been proposed, none has proven sufficiently effective, easily controllable and structurally simple to warrant its use on any wide scale. For one thing, all such devices with which I am acquainted have required some relatively inconvenient actuating movement of the foot to set or release the control, with the result that the intended advantages in facilitating driving are virtually offset by this inconvenience, and with the further result of increasing the hazards of driving by somewhat complicating the driving procedure. For instance, certain prior accelerator controls have required for setting or release a lateral movement of the right foot against a control member positioned at the side of the accelerator pedal. Another device with which I am acquainted is released by forward movement of the foot against an upstanding toe piece at the forward end of the accelerator pedal. As will be appreciated, the necessity for such lateral or forward foot movements must necessarily render the setting and release of the control rather inconvenient and thus decrease materially its practical utility.

An important object of the present invention is to provide an accelerator control adapted to be set and released with considerably greater facility than the various devices heretofore proposed. For this purpose, devices embodying the invention are constructed for control by the exertion of downward foot pressure on a depressable control member positioned near the accelerator pedal. Such downward foot pressure may of course be exerted with much greater facility and under more effective control than can the lateral or forward forces required in the devices discussed above.

To further simplify control of the device, I prefer to mount the control member for automatic actuation upon movement of a foot onto or off of the accelerator pedal. Thus as an operator places his foot on the pedal, the member may be automatically depressed to render the control device inactive and permit normal operation of the accelerator. When the foot is later removed, the control member may be automatically actuated to set the control device for retaining the accelerator in the last position to which it was moved.

2

A more particular object of the invention is to provide an accelerator control device of the above character especially adapted to be easily applicable as an accessory to any modern automobile.

5 To attain this result, as well as to increase the effectiveness of the device in operation, the preferred form of the invention comprises a specially formed accelerator pedal to be substituted for the conventional pedal and itself carrying the relatively depressable control member. The invention contemplates broadly that the depressable member may be movably mounted to the pedal in any convenient manner and at any convenient location. However, for most effective, reliable, 10 and easily controlled operation, I prefer to form the member as a relatively depressable cover plate hinged to the accelerator pedal and extending along its upper side.

In addition to the control member, the accelerator pedal preferably also carries mechanism coacting with a member attached to the floor board of the automobile to releasably retain the pedal in its set positions. This member attached to the floor board may be a flexible connector adapted to be wound about a reel carried by the pedal and releasably retainable in any of various positions for maintaining the setting of the accelerator. Particularly contemplated is a hollow elongated accelerator pedal adapted to 20 contain the reel and its control mechanism.

As will be appreciated, there might be some danger involved in the use of a device of the present character if the device were adapted to be released only by the indicated foot pressure at the accelerator location. For instance, if the accelerator were set in a given condition and it then became necessary to suddenly stop, the attempt of the operator to first engage the control member at the accelerator location for releasing the 30 accelerator and to then apply the brakes might

40 very well cause an accident. To avoid this danger, an additional object of the invention is to provide, in combination with the above improved accelerator, control mechanism for automatically releasing the accelerator from its set position upon application of the brakes. For this purpose, I may employ a simple flexible connector extending between the brake and accelerator and acting to release the accelerator as the 45 brake pedal is depressed.

It is contemplated that the accelerator positioning device may be controlled either mechanically or electrically. When electrically controlled, the apparatus may include a solenoid 50 carried within the accelerator pedal and adapted

for energization either by closing of a brake actuated switch or a control member actuated switch.

The above and other features and objects of the present invention will be better understood from the following detailed description of the typical embodiments illustrated in the accompanying drawing, in which:

Fig. 1 is a general showing of an automobile accelerator installation embodying the invention;

Fig. 2 is an enlarged horizontal section through the pedal of Fig. 1;

Fig. 3 is a vertical section through the pedal taken on line 3-3 of Fig. 2;

Fig. 4 is a fragmentary view of the rear portion of the pedal showing especially the manner in which the movable heel plate portion of the pedal may be locked in inactive condition;

Fig. 5 is a plan view of an electrically controlled second form of accelerator pedal embodying the invention, the major portion of the pedal cover being broken away to reveal the inner mechanism;

Fig. 6 is a vertical section through this second form of accelerator pedal, taken on line 6-6 of Fig. 5;

Figs. 7 and 8 are transverse sections through the pedal taken on lines 7-7 and 8-8 of Fig. 5;

Figure 9 is an enlarged fragmentary transverse section taken in the plane of Fig. 7 and showing the pawl holding latch in its holding condition; and

Fig. 10 is a diagram of the electric control circuit for this second form of the invention.

The general showing of Fig. 1 includes an automobile floor board 19, a conventional brake pedal 11, and an accelerator pedal 12 specially formed in accordance with the present invention. Accelerator pedal 12 is in certain conditions of the apparatus retained against upward movement by a flexible connector 13, typically a chain as shown, connected at its lower end to the floor board and acted upon by mechanism 14 within the accelerator pedal (see Figs. 2 and 3). Mechanism 14 is releasable to permit upward movement of the accelerator pedal by either depression of a relatively movable heel plate 15 on the accelerator or downward brake applying actuation of the brake pedal 11. For effecting such release of mechanism 14 upon application of the brakes, pedal 11 is operatively connected to mechanism 14 by a second flexible chain 16. The brake itself may comprise typically the usual tread 17 carried by an arm 18 pivotally mounted at 19 and yieldingly urged to the released Fig. 1 condition by a spring 20.

The elongated hollow accelerator pedal 12 has a bottom wall 21 and a peripheral upwardly extending side wall 22. The upper side of the pedal is closed at its forward end by tread plate 23 secured to inwardly extending flanges 24 at the upper edges of side walls 22 by screws 25. At the rear of tread plate 23, the upper side of the pedal is closed by the movable heel plate 15 whose construction and operation will be brought out more in detail at a later point.

The accelerator pedal is adapted to be conventionally mounted for vertical swinging movement about its rear portion by the usual pair of mounting elements or lugs 41 threaded into the floor board at their lower ends 42 and having ball-shaped pedal engaging heads 43 at their upper ends. For attachment to these mounting elements, pedal 12 carries near its rear end a mounting member 44 formed of rubber or similar resilient material and containing spherical recesses 45 in its underside within which heads 43 of the

43 of the mounting elements 41 are received. The resilient member 44 may be retained at its underside by a metallic plate 46, as shown. Near its forward end, the bottom wall 21 of pedal 12 carries a second resilient member 47 suitably retained to the pedal, as by screws 48, and containing a spherical socket or recess 49 within which the upper ball-shaped head 50 of the usual throttle control rod 51 is received.

The lower end of chain 13 is connected to the floor board in any suitable manner as by a screw 26 extending through and tightened against a chain carried fastening element 27. From its point of connection to the floor board, the chain extends upwardly through opening 28 in the underside of the accelerator pedal, about pulley 29 rotatably mounted to the pedal by shaft 30, and past roller 31 at the inside of the pedal for connection at its other end 32 to winding reel 33. This reel is rotatably carried about a shaft 34 projecting upwardly from the bottom wall 21 of the accelerator pedal, and is retained to the shaft by an upper pusher 35 and a retaining screw 36. Typically, the reel is illustrated as comprising a main hollow portion 37 closed at its upper side by a disk 38 retained to the main section 37 by screws 39 and having about its periphery a series of rather closely spaced ratchet teeth 40. At its inside, the reel contains a spring 52 connected at its opposite ends to the reel body and shaft 34 to normally urge the reel in a chain winding direction.

For retaining the reel against unwinding rotation in certain conditions of the apparatus, to thus retain the accelerator pedal against upward engine slowing movement, I provide a pawl 53 pivotally mounted at 54 and having an end 55 curving into engagement with ratchet teeth 40 on the reel. This pawl is connected at 56, toward its opposite end, to the brake controlled chain 16, which extends rearwardly within the pedal, and then about pulley 57 and out through opening 58 in the bottom of the pedal. After passing about pulley 57, chain 16 is directed through a guide tube 59 fastened on the floor board to extend first forwardly beneath the accelerator pedal and then laterally to a location 60 adjacent the brake pedal, from which location the chain extends upwardly for connection to the underside of the brake pedal tread 17. As will be appreciated, spring 20 normally retains the brake pedal in its released Fig. 1 condition, to thus exert a force on chain 16 retaining pawl 53 in its active Fig. 2 condition for preventing unwinding rotation of the reel. When depression of the brake pedal relieves the force exerted on pawl 53 by chain 16, the pawl is actuated to its released condition by coil spring 61 bearing at one end against the pawl and at its opposite end against an angle bracket 62 mounted to the body of the pedal. Bracket 62 may carry an elongated screw 63 extending along the inside of spring 61 for retaining it in proper position.

Heel plate 15 includes an upper tread portion 64 which may have a peripheral skirt 65 extending downwardly at the rear and sides of the pedal. At its forward end, heel plate 15 is hinged to the body of the accelerator pedal, as by a pair of screws 66 extending through the skirt 65 at opposite sides of the pedal and connecting into the pedal side walls. The heel plate is normally urged upwardly to its Fig. 3 condition by coil spring 67, which may bear at its lower end against 75 the rear mounting member 44 of the pedal.

Screw 68 projects upwardly within spring 67 to maintain the spring in its proper upwardly projecting condition. Depression of heel plate 15 is transmitted to pawl 53, to effect its retraction, by an elongated slide member 69 extending along one side wall of the pedal. This slide member is retained against the pedal wall, and guided for forward and rearward sliding movement, by a pair of guide pins 70. The forward end of slide member 69 curves inwardly for engagement at 71 with pawl 53, so that forward movement of the slide effects retracting movement of the pawl. At its rear end, slide member 69 projects rearwardly from the pedal and has an angular wedge face 72 engageable by a roller 73 carried by heel plate 15, to effect forward pawl actuating movement of the slide in response to depression of the heel plate. In order that the heel plate may on occasion be retained in its depressed condition for permitting normal operation of the accelerator, I provide at one side of the pedal a lock pin 74 extending through an elongated slot 75 in the pedal side wall 22. This pin is shiftable longitudinally within slot 75 into and out of a notch 76 in the heel plate skirt. As will be appreciated, when the heel plate is depressed, and pin 74 is shifted rearwardly into notch 76, the heel plate is positively retained in its depressed condition.

In driving an automobile equipped with the illustrated accelerator mechanism, the driver may keep his right foot on pedal 12 and actuate the pedal in entirely conventional manner. Such normal operation is possible because, when a foot is resting on the accelerator pedal, heel plate 15 is depressed to a condition actuating slide member 69 forwardly to release pawl 53 and permit rotation of reel 33 in either direction. Since movement of the reel is unrestrained, the pedal is freely movable downwardly and upwardly in response to foot movements.

When the operator desires to set the accelerator pedal in a particular condition, he merely raises his heel slightly to permit upward movement of heel plate 15, and may then remove his foot completely from the pedal. The upward movement of the heel plate permits rearward movement of slide member 69 so that pawl 53 is free for actuation, and the brake spring 20 then becomes effective through the brake pedal and connector 16 to actuate the pawl to its active Fig. 2 condition. When in its Fig. 2 condition, pawl 53 retains the reel against unwinding rotation and thus prevents upward engine slowing movement of the accelerator pedal. The automatic control is easily releasable by either replacing the foot on accelerator pedal 12 to again depress heel plate 15, or actuating the brake pedal to release the tension on chain 16.

Figs. 5 through 10 represent a variational form of the invention in which the release of the accelerator control mechanism is effected electrically. The accelerator pedal 71 of these figures includes an elongated hollow pedal body 78 movably mounted at its rear by a mounting portion 79 to a pair of spaced lugs 80, which project upwardly from floor board 81. Near its forward end, pedal body 78 is connected to the upper end of accelerator control rod 82.

In this second form of the invention, as in the first form, the accelerator setting mechanism within the pedal is releasable by either depression of the brake pedal or depression of an accelerator carried element relative to the accelerator pedal body. However, the accelerator carried element in the second form of the invention, rather than

being formed as a heel plate covering only the rear portion of the pedal, is constructed as an elongated cover or plate 83 carrying an upper tread 84 and extending along the entire upper side of the pedal body. Cover 83 may have a peripheral depending skirt 85 received about the various side walls of the pedal body 78. For effecting control of the accelerator setting mechanism, cover 83 is mounted to pedal body 78 for vertical swinging movement between the full line and broken line positions of Figs. 7 and 8 and about an axis extending along one side of the pedal. The cover may typically be mounted for such movement by a pair of screws 86 pivotally connecting the end portions of cover skirt 85 to the pedal body near one side of the pedal. Cover 83 is normally urged upwardly to its broken line position of Figs. 7 and 8 by coil spring 87, which may be centered about a positioning screw 88.

The pedal is retained in any set position by a chain 89, connected at its lower end to the floor board and at its upper end to chain winding drum 90 within the hollow pedal body. Drum 90 is urged by spring 91 in a chain winding direction and is adapted to be retained against chain unwinding rotation by engagement of pawl 92 with ratchet teeth 93 on the drum. The pawl is mounted intermediate its ends at 94 for movement between its active full line position of Fig. 5 and its inactive broken line position. Spring 95 normally urges the pawl to its active position in which the drum, chain and pedal are retained in set positions.

Pawl 92 is released by energization of a solenoid or electromagnet 96 which acts on a magnetic metal element 97 carried by a rearwardly projecting portion 98 of the pawl to swing the pawl to its broken line position. The electromagnet 40 may be mounted to the accelerator pedal body in any suitable manner as by a pair of mounting brackets 99 at its opposite sides. The energizing circuit to magnet 96 is closed, upon depression of pedal cover 83 relative to the pedal body, by actuation of control switch 100. This switch comprises a stationary contact 101 and a movable cover actuated contact 102. Contact 102 preferably takes the form of an elongated resilient arm connected at one end 103 to the accelerator body and having a vertically movable contact end 104 positioned over stationary contact 101. Contact 102 normally tends to return to an upper circuit opening condition, and is depressible to a closed condition, upon foot 45 actuated depression of the cover, by a downwardly projecting cover carried lug 105. Contacts 101 and 102 are of course suitably insulated from the pedal body, as by interposition of insulating sheets 106 between the contacts and the body.

I have discovered that unless electromagnet 96 is specially constructed for the present use, it may have a tendency to overheat or excessively drain the battery when energized for any considerable length of time. To avoid these undesired effects, I may employ an arrangement in which the electromagnet is used only for initially pulling the pawl to its released condition, the magnet not being required for maintaining the pawl in that condition after its initial actuation. For this purpose, the apparatus may include a latch arm 107 adapted to engage and hold the pawl in its released condition after actuation to that condition by the magnet. This latch arm is 70 mounted to a pedal body carried bracket 108 at

109, and is formed of spring steel to be resiliently deflectable upwardly from its normal full line position of Fig. 7 to its broken line position of that figure. Arm 107 carries near its outer free end a depending latch lug 110 engageable with a rear end portion 111 of the pawl element 92. This rear portion 111 of the pawl element is triangular in cross section, having an angular face 112 acting to engage and deflect upwardly lug 110 and latch arm 107 upon movement of the pawl to its broken line position. When the pawl reaches that broken line released position, latch lug 110 falls downwardly at the straight side 113 of pawl portion 111 to retain the pawl in released condition independently of the magnet (see Fig. 9).

Latch 107 is adapted to be automatically released in response to upward swinging movement of pedal cover 84 relative to the pedal body. For effecting such release, the cover carries a downwardly projecting element 114 carrying a horizontally extending arm 115, which is received beneath an upper horizontal portion 116 of the latch arm. Thus, as the cover swings upwardly, arm 115 engages portion 116 of the latch arm to swing the latch upwardly to its broken line released condition. Element 114 is mounted to the cover for 90 degree rotation about a vertical axis to move arm 115 from beneath portion 116 of the latch arm in order to permit removal of the pedal cover from the body without injury to the latch arm. Transverse groove 117 in the upper enlarged head portion of element 114 is accessible to a screw driver or other tool at the outside of the pedal for so rotating element 114.

Just prior to arrival at pawl 92 at its broken line position, upon energization of electromagnet 96, the energizing circuit to the magnet is automatically broken. In order to open this circuit at the proper moment, I employ a portion of the pawl element as a movable contact, which normally engages a pedal body carried contact 118, and moves out of engagement with that contact just prior to the point at which latch 107 moves to its active condition. Contact 118 may be carried by a resilient arm 119 which causes the contact to follow the motion of pawl element 92 and maintain engagement with that element until the very last portion of its movement. Contact 118 is electrically connected to contact 101, and along with that contact is insulated from the body by one of the previously mentioned insulators 106.

When the apparatus is in the condition of Fig. 5, pawl 92 prevents the chain unwinding rotation of drum 90, so that the pedal is retained in a set position. If the operator then places his foot on pedal cover 83, the cover is depressed relative to the pedal body in a manner causing cover carried lug 105 to close switch 100. Referring to Fig. 10, such closure of switch 100 closes an energizing circuit from car battery 120 to electromagnet 96 through switch 100, contact 118, and pawl element 92. The electromagnet then draws the pawl to its broken line released position in which it is retained by latch 107; the magnet energizing circuit being broken as the pawl reaches its broken line position by movement of the pawl element away from contact 118. With the pawl in its released condition, drum 90 is free to rotate and the pedal may be freely operated without effect by the setting mechanism. If the operator desires to again set the accelerator at a particular position, he slightly raises the right side of his foot in a

5 manner permitting upward swinging movement of cover 83 while maintaining the pedal body in the desired position, and arm 115 of cover carried element 114 then acts to release latch 107 and permit return of the pawl to its Fig. 5 condition.

In order that the accelerator setting mechanism may be automatically released upon application of the brakes, as well as in the above defined manner, I provide for energization of solenoid 96 in response to closure of the usual brake actuated switch 121 which closes the circuit to stop light 22 (see Fig. 10). For this purpose, stop light switch 121 is connected into a second energizing circuit leading from battery 120 to the magnet.

I claim:

1. Automobile speed control mechanism comprising an accelerator pedal to be mounted in an automobile for speed controlling movement toward and away from a floorboard, a flexible member to be fastened at its lower end against upward movement relative to the floor board, a reel carried by the pedal for winding the upper end of the flexible member, a holding part movably carried by said pedal adapted to act against and prevent unwinding rotation of the reel from any of a plurality of positions to thereby releasably restrain engine slowing movement of the pedal from any of progressive positions in its range of movement, and foot controlled means carried by said pedal for releasing said holding part.

2. Automobile speed control mechanism comprising a hollow accelerator pedal to be mounted in an automobile for speed controlling movement toward and away from a floorboard, a member to be fastened to the floorboard against bodily upward movement relative thereto and extending into said hollow pedal, means in said pedal cooperating with means associated with said member to releasably restrain engine slowing movement of the pedal from any of progressive positions within its range of movement, and foot controlled means carried by said pedal for releasing said restraining means to permit engine slowing movement of the pedal.

3. For use in association with a spring retracted brake pedal, a floorboard, and throttle mechanism in an automobile; an elongated hollow accelerator pedal for actuating said throttle mechanism and adapted to be mounted for speed controlling movement toward and away from the floorboard, a flexible member connectable at its lower end to the floorboard and extending upwardly into said hollow accelerator pedal, a reel in the accelerator pedal for winding the flexible member, a spring urging said reel in a winding direction, said reel having a series of teeth spaced thereabout, a movable pawl acting against said teeth to releasably retain the reel in any of a plurality of positions and to thereby restrain upward movement of the accelerator pedal from any of a plurality of progressive positions within its range of movement, a spring urging said pawl to released condition, a flexible connector for operatively interconnecting said pawl and brake pedal so that the pawl is normally retained in active reel restraining condition by the force of the brake retracting spring and is released by actuation of the brake pedal, a cover extending across the upper side of said hollow accelerator pedal and hinged to the pedal for depression relative thereto, a spring urging said cover upwardly relative to the accelerator pedal.

and means operable by depression of said cover relative to the pedal to release said pawl.

4. Automobile speed control mechanism comprising an accelerator pedal to be mounted in an automobile for speed controlling movement, means for releasably restraining engine slowing movement of the accelerator pedal from any of progressive positions in its range of movement, a foot operated member carried by and movable relative to said pedal, and electrical control means carried by said pedal responsive to movement of said member to actuate said restraining means between active and released conditions, said control means including an electrical switch actuatable by said foot operated member an electric solenoid carried by said pedal and responsive to actuations of said switch, and a movable control member operable by the solenoid.

5. Automobile speed control mechanism comprising an accelerator pedal to be mounted in an automobile for speed controlling movement toward and away from a floorboard, a flexible member to be fastened at its lower end against bodily upward movement relative to the floorboard, a reel about which an upper end of said member is wound and mounted to the pedal for rotation about an axis extending generally in said direction of the pedal movement, means mounting the reel for said rotation about said axis, means carried by the accelerator pedal operable to prevent unwinding rotation of the reel from any of a plurality of positions to thereby releasably restrain engine slowing movement of the pedal, and foot controlled means carried by said pedal for releasing said restraining means to permit engine slowing movement of the pedal.

6. Automobile speed control mechanism as recited in claim 5, in which said pedal is elongated and hollow and contains a chamber having its smallest dimension in said direction of pedal movement, said reel being contained within in said chamber.

7. Automobile speed control mechanism as recited in claim 1, in which said reel has a series of teeth spaced thereabout, and said holding part comprises a movable pawl acting against said teeth.

8. Automobile speed control mechanism comprising a hollow accelerator pedal to be mounted in an automobile for speed controlling movement toward and away from a floorboard, a member to be fastened to the floorboard against bodily upward movement relative thereto and extending upwardly into said hollow pedal, means in said pedal cooperating with means associated with said member to releasably restrain engine slowing movement of the pedal from any of progressive positions within its range of movement, an electric solenoid in said hollow pedal controlling the actuation and release of said restraining means, and a foot operated switch carried by said pedal and controlling said solenoid.

9. For use in association with a spring retracted brake pedal, a floorboard, and throttle mechanism in an automobile; an elongated hollow accelerator pedal for actuating said throttle mechanism and adapted to be mounted for speed controlling movement toward and away from the floorboard, a flexible member connectable at its lower end to the floorboard and extending upwardly into said hollow accelerator pedal, a reel in the accelerator pedal for winding the flexible member, a spring urging said reel

in a winding direction, said reel having a series of teeth spaced thereabout, a movable pawl acting against said teeth to releasably retain the reel in any of a plurality of positions and to thereby restrain upward movement of the accelerator pedal from any of a plurality of progressive positions within its range of movement, a spring urging said pawl to a first position, an electric solenoid in said pedal operable to actuate the pawl against the tendency of the spring to a second position, a cover extending across the upper side of said hollow accelerator pedal and hinged to the pedal for depression relative thereto, a spring urging said cover upwardly relative to the pedal, and a switch operable by depression of said cover relative to the pedal and controlling energization of said solenoid.

10. Speed control mechanism comprising an accelerator pedal to be mounted in a motor vehicle for speed controlling movement toward and away from a floorboard, a flexible member to be fastened against bodily upward movement relative to the floorboard, holding means carried by said pedal for movement relative thereto and operable to cooperate with means associated with said flexible member and to thereby releasably restrain engine slowing movement of the pedal from any of progressive positions in its range of movement, and foot controlled means carried by said pedal for actuating said holding means in response to manipulation of a driver's foot.

11. Speed control mechanism as recited in claim 10, including a fastening element carried by a lower end of said flexible member and adapted to be removably attached to the floor board of a motor vehicle

12. Speed control mechanism as recited in claim 10, in which said pedal is hollow and contains a rotatable reel about which an upper portion of said flexible member is windable, and said holding means act to restrain unwinding rotation of said reel.

13. Automobile speed control mechanism as recited in claim 2, in which said foot controlled means includes a cover extending across and closing an upper side of the pedal and movable relative thereto by manipulation of a driver's foot, and means carried by the pedal for actuating said restraining means in response to movement of said cover.

14. Speed control mechanism comprising an accelerator pedal to be mounted in a motor vehicle for speed controlling movement toward and away from a floorboard, a member to be fastened against bodily upward movement relative to the floorboard, holding means carried by said pedal for movement relative thereto and operable to cooperate with means associated with said member and to thereby releasably restrain engine slowing movement of the pedal from any of progressive positions in its range of movement, electrically energized means for actuating said holding means, and foot operated means controlling actuation of said electrically energized means in response to manipulation of a driver's foot.

15. Speed control mechanism as recited in claim 14, in which said pedal is hollow and contains said holding means and electrically energized means, said member being flexible.

16. Speed control mechanism as recited in claim 15, including a reel contained in said hollow pedal and rotatable relative thereto about an axis extending generally in the direction of

pedal movement toward and away from the floor-board, said flexible member being windable about said reel, said holding means acting to restrain unwinding rotation of the reel.

17. Speed control mechanism as recited in claim 16, in which said electrically energized means includes an electric solenoid for actuating the holding means, said foot operated means including a cover for the pedal mounted for movement relative thereto, and an electric switch controlling said solenoid and actuated by said cover, said apparatus including means for connecting said electrically energized means to an electric switch actuated by the brake of the vehicle to be responsive to actuation thereof.
